MACHINE FOR PICKLING, SWILLING, AND SCRUBBING METAL PLATES

Samuel Davies, Briton Ferry, Wales, assignor of one-half to Saml. Davies: Alexander Engineering Works Limited, Briton Ferry, Wales, a company of Great Britain

Application April 1, 1935, Serial No. 14,162
In Great Britain April 3, 1934

12 Claims. (Cl. 266—7)

This invention relates to machines for pickling, swilling and scrubbing metal plates in the tin and terne plate industry.

For the purposes of efficiency and economy, it is important in this industry to be able to deal expeditiously with relatively large numbers of plates and in the general practice the plates, in suitable batches, are pickled and washed in bulk. This is effected in a separate machine and then the batches of plates are transported to a tinning machine and the plates passed one after another through this machine for the purpose of coating them with metal.

When the plates are pickled and washed in bulk, the treatment liquids do not always effectively reach the whole surface of the plates, and the subsequent removal of the plates to the tinning machine involves a multiplicity of operations.

The object of the present invention is to provide an improved machine which enables the plates to be treated separately or singly and a much more effective and uniform application of the liquids to the plate surfaces to be achieved. The machine is at the same time capable of treating plates in succession so that they may be treated in sufficiently large numbers and be passed directly after washing and scrubbing to a tinning machine. In the treatment of plates separately and in succession, however, it is necessary to have regard to the fact that plates of different lengths have to be dealt with in practice and therefore the invention provides for the improved machine also to be capable of dealing with plates of this nature in an effective and economical manner.

It may here be mentioned that small plates are of different lengths from large plates. The length is as regarded in the direction in which the plates are passed through the machine and when referring to the length of the plates in this specification the dimension in that direction is what is intended. Naturally only plates of one length are treated at any one time.

According to this invention, a pickling device is provided comprising a plate carrier suitable for receiving plates separately or singly and in succession and adjustable to suit the length of plates under treatment, and means operative to discharge the plates from the pickling bath or vat in succession at substantially equal intervals or distances apart for all lengths of plates. The device suitably comprises a reciprocatory or jiggling plate carrier which is adjustable to suit plates of different lengths, and a pick-up device which is operative at different speeds, according

to the length of the plates, for discharge of the plates from the plate carrier in succession at substantially equal intervals or distances apart. The invention also provides a feed device operative at corresponding speeds to feed the plates to the pickling bath or vat. Cam or like mechanism may be used for effecting jiggling movement of the carrier and the arrangement is suitably such that several reciprocations are imparted to the carrier before the pick-up device comes into action to bring about removal of the respective plates from the bath or vat. By this apparatus effective treatment of the plates by the liquid may be achieved and as the plates can be removed at substantially equal successive intervals or distances apart irrespective of their dimensions in the direction of travel through the machine, there need be no waste of space and time in the delivery of the plates and plates of all normal sizes can be treated effectively and economically.

For the purpose of swilling and scrubbing the plates or freeing them from acid, it is convenient to employ a swilling and scrubbing device comprising one or more sets of traversing rolls and one or more sets of cleaning rolls which rotate at different peripheral speed from the traversing rolls. With this arrangement the cleaning rolls are able to effect a scrubbing or wiping of the plates resulting in very effective washing or cleaning.

In order to enable the invention to be readily understood reference is directed to the accompanying drawings in which:

Figure 1 is a side elevation of one form of machine in accordance with these improvements.

Figure 2 is a transverse sectional elevation of the pickling vat and mechanism.

Figure 3 is a composite longitudinal sectional elevation on the lines III—III and IIIa—IIIa of Figure 2.

Figure 3a is a fragmentary view illustrating a modification.

Figure 4 is a section on the line IV—IV of Figure 2.

Figures 5 and 6 are respectively side and end elevations of a coupling for the shaft of the abutment roll hereinafter referred to.

Figure 7 is a plan of the swilling and scrubbing device, and

Figure 8 is a fragmentary view, corresponding to Figure 4, of a modified construction of pick-up device.

As seen in Figures 1 to 4, the machine comprises a pickling section A, a feed section B and a

swilling and scrubbing section C which may be 5 separately installed, or mounted together on a common frame or base. The pickling tank or vat a is of rectangular form open at the top and fitted with a removable frame for the plate carrier and pick-up device hereinafter described. This frame comprises two end plates b joined by two tie-rods c, d at the top and by a cross-member e and a tie-rod e' (Figures 3 and 4) at the bottom. The frame is carried by the projecting ends of the tie-rods c, d resting between stops c', d', upon pedestals or supports f on the side walls of the vat. The plate carrier g is made of U form (Figure 2) from metal strip and has a straight bottom part on which are provided a series of rests h for the lower edge of the metal plates. In order to suit the carrier to different lengths of plate, it has a series of holes or pegs as at i (Figures 3 and 4) at the upper part of the arms of the U for the purposes of mounting it in vertically adjustable position upon two levers k respectively mounted on the end plates b of the aforesaid frame. These levers are adapted to be oscillated on their pivots l, to reciprocate or jig the carrier, by means of cams m. It is convenient to employ a three-lobe form of cam, see Figure 3, and to mount the cams on the spindle of a plate-discharge roll n which is mounted in bearings in slots such as j in the frame plates b. The levers k are of three-armed nature and the cam action is applied to the arms o. The cams operate to depress the plate carrier g, the return movement being caused by spring means or weights p operative on the free arms of the levers k. The plate-discharge roll n operates in conjunction with a press-roll r carried at one end of a pair of levers s mounted on the tie-rod d springs or weights t being provided at the other ends of the levers to press this roll against the discharge roll. The rolls n and r may be rubber-covered. The pick-up device comprises a number of arcuate pressure-shoes u of acid-resisting metal carried by bow-springs v mounted on a spindle w which is supported in bearings in the frame-plate b and driven in the manner hereinafter described. In the machine shown, wherein the vat a is made wide enough for operation on two plates side by side, there may be four of these pressure-shoes u, two for each plate, mounted at appropriate intervals along the spindle w, see Figure 2. The plates side by side are adapted to be alternately lifted by the pick-up device into engagement with the plate-discharge and press rolls n, r and therefore the respective pairs of pressure-shoes u are mounted diametrically opposite each other on their spindle w. The pressure-shoes operate in conjunction with an abutment roll x mounted in bearings in the frame plates b and the spindle w is fitted with a pair of toothed segments y, which are diametrically oppositely disposed and adapted to gear at appropriate times with a gear wheel z on the abutment-roller spindle 1. It is to be noted that the spindle w is shown in Figure 2 as turned 90° with respect to the position seen in Figures 3 and 4, the object being to show clearly the diametrically opposite disposition of the pairs of pressure-shoes u and the segments y. The arcual length of the pressure-shoes u is slightly greater than the distance which the plates are required to be lifted to bring them into engagement with the plate-discharge and press rolls n, r, and the arcual length of the toothed segments y is such as to cause corresponding revolution of the abutment roll x. If desired, the

two segments y may be replaced by a complete toothed wheel as illustrated by the wheel y' in Figure 3a. This would cause the abutment roll x to rotate continuously but that would not be any disadvantage because such roll is only effective to lift the plate when the pressure shoes u are in operative position. 5

The frame aforesaid is fitted with two vertical series of bars 2 spaced slightly in front of the abutment roll x to keep the plates in upright position when the pressure-shoes u are in inoperative position. These bars are bent over at the bottom, as at 2a, and riveted to the cross-member e of the frame, and bent forwardly at the top and engaged with the tie-rod c. The bars are 10 appropriately spaced apart and the pressure-shoes u of the pick-up device are operative between the bars. Forwardly curved guides 3 extend upwardly from the tie-rod d to direct the discharged plates to guides 4, Figure 1, leading to a swilling and scrubbing device hereinafter described. 15

Feed of plates to the pickling vat is effected by a feed device, Figure 1, comprising a pair of fly frames 5 and respective feed belts, such as 6, 25 disposed side by side. The fly frames 5 are respectively mounted on two directly-gearied spindles 7, carried in brackets such as 8 on a framing 9, and they are operated by a crank and linkage mechanism 10, 11, 12 from the driving 30 spindle 13 of the pick-up device, Figures 1 and 2, the arrangement suitably being such that when one fly-frame is swung down to deposit a plate on its feed belt, the other is swung up to have a 35 plate placed on it by the operator from a table or bench 14, and vice versa. The feed belts 6 are upwardly inclined and carried on rollers, such as 15, mounted in bearings on the framing 9 and they deliver the plates by way of guides 16, 17 into the vat a in the neighbourhood of the 40 pick-up abutment roll x. Each fly frame suitably comprises a pair of arms, such as 18, fixed on one of the spindles 7, joined by an adjustable rest 19 for the plates and fitted on the outer side with guide ears such as 20 for the sides of the 45 plates. The arms 18 of each fly frame are spaced apart sufficiently to pass the sides of the respective feed belt 6 on the downward stroke to enable the frame to deposit its plate, and the lower feed-belt rollers 15 are disposed out of the path of the 50 adjustable rests 19 so as not to interfere with this movement of the arms. If desired, nip rolls such as 21, may be mounted at the upper end of the feed belts 6 to facilitate feed of the plates to the pickling vat, a. 55

In order to bring about discharge of the successive plates at substantially equal intervals or distances apart from the pickling vat, the pick-up device, together with the plate-discharge roll, the fly frames and the feed belts, is adapted to 60 be operated at different speeds according to the length of the plates and for this purpose a change-wheel and chain or equivalent drive is provided as will now be described with reference to Figures 1, 2, and 7. At the swilling and scrubbing 65 device C is a drive shaft 23 having a sprocket pinion 24 thereon over which the lower run of a drive chain 25 is engaged. The chain 25 extends in one direction from the pinion 24 to a jockey or idler sprocket 26 and in the other direction to a change-wheel sprocket 27 which is removably mounted on the spindle of the plate-discharge roll n of the pickling device, the upper run of the chain extending directly between the change sprocket and the idler sprocket. The 70 75

driving spindle 13 of the pick-up device is operated by sprocket and chain or equivalent drive 28 from the discharge-roll spindle, a convenient driving ratio being 1-3, and it will be realized that by the use of appropriate change-wheel sprockets 27, the feed fly-frames and the pick-up device can be operated at any desired speed to suit plates of different lengths. An appropriate amount of slack is provided in the lower run of the driving chain 25, between the drive sprocket 24 and the change wheel sprocket 27, to accommodate change wheels of different diameters.

The feed belts 6 are conveniently driven by a sprocket chain 29 extending between a sprocket wheel 30 on the spindle of the plate discharge roller *n* and a sprocket wheel 31 on the spindle of the upper feed-belt rollers 15.

The driving spindle 13 of the pick-up device is mounted in an appropriately packed bearing 13^a in one side wall of the pickling vat and in a bearing bracket 13^b mounted on that wall, see Figure 2, and it is connected by a coupling 32 with the pressure-shoe spindle *w* of the pick-up device. This coupling 32 as shown in Figures 5 and 6, comprises a member 33 of bar-like form on the shaft 13 and a companion member 34 of rectangular (or it may be circular) form on the spindle *w*, the bar 33 engaging a recess 35 in the member 34. With this construction, the coupling parts can be engaged laterally with each other, thus allowing the plate-carrier and pick-up frame aforesaid to be bodily inserted into or lifted from the vat *a* without disturbing the pick-up driving spindle 13. The ends of the bar coupling member 33 may be tapered off, as shown, to facilitate engagement of the coupling parts.

The swilling and scrubbing device C is arranged forwardly of the pickling vat *a* and suitably comprises a tank 36, Figures 1 and 7, fitted with a pair of rubber-faced plate-traversing rolls 37 and two pairs of scrubbing or wiping rolls 38, 39 of slightly larger diameter faced with cork or like material. The traversing rolls may be placed centrally in the tank with a pair of wiping rolls on either side as shown, and the bearings of the several rolls are suitably mounted in open-top slots in frames or supports 40, bolted to the bottom of the tank 36, so that the rolls may be removed easily from the tank. The drive for the rolls is by three separate shafts 41, 42, and 23 (the latter already referred to) which are mounted at one side of the tank 36 on supports 360, Figure 2, and have spur or like wheels 43, 44, 45, at their inner ends meshed with wheels 46, 47, 48 respectively on the adjacent ends of the spindles of the lower rolls of the sets 38, 37, 38. The jockey or idler sprocket 26 aforesaid is mounted revolvably on the shaft 41. The shafts 41, 42 and 23 are removably mounted to allow removal of the rolls 37, 38, 39, as aforesaid and the drive to them is as follows: On the shaft 41 is a sprocket 49 to which drive is transmitted by a chain 50 driven, say, from the entry or feed rolls of a tinning machine hereinafter referred to. The sprocket 49 preferably has a dog clutch 49^a associated with it so that the drive may be connected and disconnected as desired. Also on the shaft 41 is a second sprocket 51 which transmits drive through a chain 52 to a sprocket 53 on the shaft 42. The latter in turn has a second sprocket 54 and this transmits drive through a chain 55 to a sprocket 56 on the shaft 23. The upper rolls of each pair of rolls 37, 38 and 39 are driven from the spindles of the respective lower rolls 75 by spur or like gears of 1-1 ratio located at 70

at the opposite ends of the roll spindles to the wheels 46, 47, 48. The drive ratios adopted for the driving gearing of the rolls, 37, 38, 39 and the size of the rolls themselves are suitably such that the traversing rolls 37 revolve at a greater 5 peripheral speed than the first pair of scrubbing or wiping rolls 38, while the second pair of scrubbing or wiping rolls 39 revolves at a greater peripheral speed than the traversing rolls 37, the speed suitably being about four times as fast in 10 each case. This progressively increasing speed of the successive sets of rolls 38, 37, 39 prevents buckling of the plates between such rolls during the scrubbing and swilling treatment. Water-jet devices 57, mounted on the frames 40, may be 15 placed forwardly of the second set of wiping rolls 39 to complete the washing or swilling of the plates and beyond these jets a pair of delivery rolls 58 may be placed from which the plates may pass direct to a tinning or like machine. 20 The bearings of the rolls 58 may be mounted in open-top slots in frames such as 59 carried on brackets such as 60, disposed one on each of the frames 40 aforesaid, and the rolls may be geared together by gearing of 1-1 ratio at 71 and be 25 driven by extending the driving chain 25 aforesaid from the idler 26 over a sprocket 61 on the spindle of the lower roll as shown. The delivery rolls 58 are rotated at a slower peripheral speed than the last set of scrubbing or wiping rolls 39 30 in order to prevent too rash feed of the plates to the tinning or like machine, and buckling of the plates between the pairs 39 and 58 may be prevented in any suitable manner as by arranging for the delivery rolls to allow slip until the plates 35 leave the rolls 39. The distance between the pair 39 and the pair 58 is enough to allow very thin plates to bow without buckling and damaging them. The rolls of each pair in the washing tank 36, may be pressed resiliently together by 40 springs or weights or by hand-screws such as 62 mounted in the roll-bearing retaining plates 62^a. In Figure 1, parts have been cut away, along the line 1-1 of Figure 7, for clearness of illustration.

In the operation of the apparatus, the plate carrier *g* in the pickling vat *a* is first adjusted to suit the length of the plates to be treated. This is effected by engaging the appropriate pegs or holes at *i* with the levers *k* and the adjustment effected is such that whatever the length of the 50 plates, the upper edges of the latter are about at a constant distance from the plate-discharge roll *n* when they are placed in the carrier. As a suitable working figure, this distance, measured from the top of the plate to the nip of the roll 55 is approximately three inches less than the circular length of the pick-up pressure-shoes *u*, so that the latter will raise the plates a sufficient distance to be effectively nipped by the rollers *n*, *r*. The initial adjustments also include the 60 selection of an appropriately-sized change sprocket at 27 to suit the length of plates being dealt with. The apparatus is now set in motion and the operator places the black plates alternately on to the two fly frames 5 of the feed device. By 65 the operation of the crank and linkage mechanism 10, 11, 12, the fly frames are swung down alternately to transfer the plates to the feed belts 6 and from the latter they pass one after another between the nip of the rolls 21 and the belts 6 and 70 by way of the guides 16, 17 to the pickling vat *a* where they come to rest in an upright position in the plate carrier *g* in front of the bars 2, as seen for instance at 43 in Figure 4. The plate carrier is, of course, being subjected to up-and-down 75

reciprocatory or jiggling movements by the cams *m* and this causes corresponding movements of the plates so that they are effectively treated by the acid in the vat. After several jiggling movements the pressure shoes *u* of the pick-up device come, by rotation of their spindle *w*, into contact with the respective plates so that the latter are gripped between the pressure shoes and the abutment roll *x*. The latter is rotated by the appurtenant toothed segments or wheel at *y* on the pressure-shoe spindle *w* and if the drive is by segments, the roller *x* only rotates when a plate is being lifted. The pick-up device thus brings the side by side plates alternately to the plate-discharge and press-rolls *n*, *r* and from these the plates are successively guided by the guides *4* to the swilling and scrubbing tank *36*. As will be realized, small plates will be operated at greater speed than large plates both during feed to the pickling vat *a*, and during discharge therefrom, and consequently the plates, on delivery, will be at approximately equal intervals or distances apart whatever the length of the plates, so that uniform and high speed operation is attainable.

On reaching the swilling and scrubbing tank, each plate first enters the nip of the first pair of wiping rolls *38* and is then taken up by the traversing rolls *37*. As the rolls *37* move with a greater peripheral speed than the rolls *38*, a scrubbing or wiping action is exerted by the latter rolls on the plate which is now moved into the nip of the second pair of wiping rolls *39* which, owing to their greater peripheral speed, effect further wiping or scrubbing of the plate. The plate is then taken up by the guide *63* and passed to the water jet *57* by which it is given a final wash-off on each side and it then passes to the delivery rolls *58* which deliver it directly to the tinning or coating machine assisted by a suitable guide such as *64*. The delivery rolls *58*, or an extra pair of delivery rolls, may be placed before the jet devices *57* if desired. A convenient construction of tinning or coating machine is described in the specification accompanying our concurrent patent application Serial No. 14,161 of even date herewith.

In practice, the substantially equal spacing of the plates on discharge from the pickling bath or vat, can be maintained to a favourable extent through the swilling and scrubbing device and the tinning or like machine, with consequent advantage in the manufacture of coated metal plates.

All parts of the pickling vat mechanism would, of course, be of acid resisting material. The mechanism described provides a very efficient pickling action, but it will be understood that modifications may be made in the construction of this mechanism and also of the mechanism of the feed and swilling and scrubbing apparatus without departing from the scope of this invention.

An advantageous modification of the pickling mechanism is seen in Figure 8, and consists in using one or more metal plates *65*, instead of the series of bars such as *2* aforesaid, for maintaining the pickling plates *43* in upright position in the carrier *g*. The pressure-shoes *u* of the pick-up device would be arranged to engage these plates *65*, instead of engaging the pickling plates, and by mounting the plates *65* in vertically movable manner on the carrier and pick-up frame, for instance by a lost-motion connection *66* be-

tween it and the spindle of the plate-discharge roll *n*, the said plates can rise with the respective pickling plates as the latter are lifted for discharge. The pressure-shoes press the plates *65* against the pickling plates and the latter against the abutment roller *x* to effect the lifting movement and thus there is no direct pressure of the shoes on the pickling plates which is an advantage, for example, when thin plates are being pickled as it avoids denting the plates by the shoes. These loose plates *65* may be guided at the lower end by a bar *67* extending between the frame plates *b* and may be perforated if desired to facilitate the access of pickling liquid to the pickling plates.

I claim:—

1. Apparatus for pickling metal plates, comprising a pickling vessel and a plate-carrier operative in said vessel, adapted to receive plates separately and in succession, means for adjusting said plate carrier to suit different lengths of plates, means operative to jig said plate-carrier, plate-discharge means operative to remove each plate from said plate-carrier after allowing several jiggling movements of the plate but before the next following plate is received in said plate carrier and means for operating said plate discharge means to discharge the plates from said pickling vessel in succession at substantially equal intervals apart for all lengths of plates.

2. Apparatus for pickling metal plates, comprising a plate-carrier adapted to receive plates separately and in succession, means for adjusting said plate carrier to suit different lengths of plates, means operative to jig said plate-carrier, means adapted to come into operation intermittently to grip the plates and, remove them in succession from said plate-carrier, and means for adjusting the time and speed of operation of said gripping means to suit different lengths of plates.

3. Apparatus for pickling metal plates, comprising a pickling vessel, a plate-carrier operative in said vessel and adjustable to suit different lengths of plates, means operative to jig said plate-carrier, means adapted to come into operation intermittently to grip the plates and remove them in succession from said plate-carrier, means for adjusting the time and speed of operation of said gripping means to suit different lengths of plates, and a plate-discharge roll operative at different speeds, according to the lengths of the plates, to discharge the plates from said vessel.

4. Apparatus for pickling metal plates, comprising a pickling vessel, a plate carrier operative in said vessel and adjustable to suit different lengths of plates, means operative to jig said plate carrier, a feed device operative at different speeds to feed the plates successively to said pickling vessel and plate carrier, and plate-discharge means operative to remove each plate from said plate-carrier after allowing several jiggling movements of the plate but before the next following plate is received in said plate carrier and means for operating said plate discharge means to discharge the plates from said pickling vessel in succession at substantially equal intervals apart for all lengths of plates.

5. Apparatus for pickling metal plates, comprising a plate-carrier adapted to receive plates separately and in succession and adjustable to suit different lengths of plates, a multi-lobe cam operative to jig said plate-carrier, and plate-

- discharge means operative to remove each plate from said plate-carrier after allowing said multi-lobe cam to effect several jiggling movements of the plate.
5. 6. Apparatus for pickling metal plates, comprising a pickling vat, a plate feed device comprising a swingable fly frame and a travelling feed belt, a plate carrier mounted in said vat and adjustable to suit the length of plates under treatment, a multi-lobe cam for jiggling said plate carrier, a revolvable pressure shoe for removing plates from said plate carrier after allowing several jiggling movements of such plates, and a change-wheel shaft having driving connection with said fly frame, feed belt, cam and pressure shoe.
10. 7. Apparatus for pickling metal plates, comprising a jiggling plate carrier which is adjustable to suit plates of different lengths, a pick-up device comprising a resiliently-mounted pressure-shoe and a co-operative abutment roll operative for discharging the plates from said plate carrier in succession, and means for adjusting the time and speed of operation of said pressure-shoe and abutment roll to suit different lengths of plates.
20. 8. Apparatus for pickling metal plates, comprising a jiggling plate carrier which is adjustable to suit plates of different lengths, a pick-up device comprising a resiliently-mounted pressure-shoe and a co-operative abutment roll operative for discharging the plates from said plate carrier in succession, means for adjusting the time and speed of operation of said pressure-shoe and abutment roll to suit different lengths of plates, and means for maintaining the plates in upright position in said plate-carrier when said pressure-shoe is in inoperative position.
30. 9. Apparatus for pickling metal plates, comprising a jiggling plate carrier which is adjustable to suit plates of different lengths, a pick-up device comprising a resiliently-mounted pressure shoe and a co-operative abutment roll operative for discharging the plates from said plate carrier in succession, means for adjusting the time and speed of operation of said pressure-shoe and
35. 10. Apparatus for pickling metal plates, comprising a pickling vessel, a frame removably mounted in said vessel, a plate carrier mounted in said frame and adjustable to suit plates of different lengths, jiggling means mounted in said frame and operatively connected with said plate carrier, a pick-up device also mounted in said frame, said pick-up device being adapted to come into operation intermittently to remove plates in succession from said plate carrier, and means for adjusting the time and speed of operation of said pick-up device to suit different lengths of plates.
25. 11. Apparatus for pickling metal plates, comprising a pickling vessel, a plate carrier operative in said vessel and adjustable to suit different lengths of plates, a feed device for feeding the plates successively to said vessel and plate carrier and comprising a swingably-mounted fly frame and a cooperative feed belt, means for driving said fly frame and feed belt at different speeds to suit different lengths of plates, and means operative to discharge the plates from said plate carrier and vessel in succession at substantially equal intervals apart for all lengths of plates.
30. 12. Apparatus for pickling, swilling and scrubbing metal plates, comprising in combination a pickling vat, a plate carrier operative in said vat and adjustable to suit plates of different lengths, means operative to discharge the plates from said carrier and vat in succession at substantially equal intervals apart for all lengths of plates, and a plate swilling and scrubbing device comprising sets of traversing and cleaning rolls for receiving plates discharged from said pickling vat, and means for rotating said sets of rolls at progressively increasing peripheral speeds from the first set to the last.

40 45
SAMUEL DAVIES.
